Primary Examiner — Joseph Kukella*Assistant Examiner* — Heather Wencl(74) *Attorney, Agent, or Firm* — Paratus Law Group, PLLC(57) **CLAIM**

The ornamental design for a belt strap adjuster, as shown and described.

DESCRIPTION

FIG. 1 is a front, top, and right perspective view of a belt strap adjuster showing claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, top, and right perspective view thereof, showing a state in which a hook portion is unhooked;

FIG. 9 is a cross-sectional view taken along line 9-9 shown in FIG. 2; and,

FIG. 10 is a reference view showing the belt strap adjuster in use.

The broken lines shown in FIGS. 3 and 4 depict portions of the belt strap adjuster that form no part of the claimed design. The broken lines shown in FIG. 10 depict environment and form no part of the claimed design.

1 Claim, 5 Drawing Sheets(56)
